[57] CLAIM

The ornamental design for a foldable beach equipment carrier, as shown and described.

DESCRIPTION

FIG. 1 is a front perspective view of a foldable beach equipment carrier showing our new design;

FIG. 2 is a side elevational view, the opposite side view being a mirror image thereof;

FIG. 3 is a top plan view thereof,

FIG. 4 is a bottom plan view thereof,

FIG. 5 is a rear elevational view thereof; and

FIG. 6 is a front elevational view thereof,

FIG. 7 is a front perspective view of a second embodiment of FIG. 1;

FIG. 8 is a side elevational view, the opposite side being a mirror image thereof;

FIG. 9 is a top plan view thereof,

FIG. 10 is a bottom plan view thereof,

FIG. 11 is a rear elevational view thereof,

FIG. 12 is a front elevational view thereof,

FIG. 13 is a perspective view of the embodiment of FIG. 1 with the shelves in closed position; and

FIG. 14 is a side elevational view of the embodiment of FIG. 1 shown in folded position.
